UNITED STATES PATENT OFFICE.

JOHN H. LORIMER, OF PHILADELPHIA, PENNSYLVANIA.

DRYING AND CONDITIONING MACHINE.

No. 811,807.

Specification of Letters Patent.

Patented Jan. 30, 1906.

Application filed May 20, 1905. Serial No. 261,365.

To all whom it may concern:

Be it known that I, JOHN H. LORIMER, of the city and county of Philadelphia and State of Pennsylvania, have invented an Improvement in Drying and Conditioning Machines, of which the following is a specification.

My invention has reference to drying and conditioning machines for textile and other materials; and it consists of certain improvements, which are fully set forth in the following specification and shown in the accompanying drawings, which form a part thereof.

In drying-machines of the class to which this improvement relates I have heretofore employed two endless aprons of meshed or open material operating in pairs and holding the wool or other material between them while being conveyed through the drying-chamber and the vertical currents of air put into circulation through the aprons. In such machines the aprons passed horizontally through the chamber, and while the lower apron supported the textile material the upper apron pressed heavily upon it. In the reverse transit through the chamber the upper apron takes the lower position and supports the textile material with the other apron pressing down upon it. While the two aprons are necessary because of this reversal and also for conveying the textile material to different levels and around the guide-wheels, the pressure of the upper apron-section upon the material when traveling horizontally is very objectionable on some materials, as it tends to compress the material and prevent proper permeation of the drying medium, be it air or gas.

The object of my present improvement is to provide a drying-machine of this character with both drying and conditioning chambers, each of which are provided with means for separating the aprons where they pass horizontally, or substantially so, whereby while confining the material between the aprons it is permitted to be in proper condition to be readily permeated by the air in the drying-chamber and the air, steam, or gases in the conditioning-chamber driven through them under the action of the blowers. The extent of separation of the aprons will vary with the materials being treated, and I am enabled to have any separation desired to suit the conditions best adapted for the materials being dried.

My invention consists of a case having two chambers through which air, steam, or gases circulate, as required or desired, in a vertical

direction, combined with apron-guide wheels, two endless aprons of open-work which are caused to pass successively through both the drying and conditioning chambers, and guides in each of the chambers for guiding the said aprons at a distance apart during their travel horizontally between the guide-wheels, but permit of their lying close together in passing about the said guide-wheels when being raised or lowered from one level to another.

My invention also comprehends details of construction which, together with the features above specified, will be better understood by reference to the drawings, in which—

Figure 1 is a longitudinal sectional elevation of a drying and conditioning machine embodying my invention. Fig. 2 is a cross-section of same on line 2,2; and Fig. 3 is an enlarged view of a portion of Fig. 2, showing the independent guides for the two aprons.

A is the drying-chamber, and P the conditioning-chamber, and are each preferably furnished with a side chamber H, in which may be placed heating-coils N and the fans I. The fans draw air downward through the chambers A and P and force it upward over the heating-coils, from which it passes by passage J into the top of the chambers A and P again. Doors T may be used to allow escape of damp air and entrance of fresh air. An injector or nozzle R may be used to admit steam or gases to the conditioning side chamber H.

B and C are two endless aprons which are caused to travel close together for a portion of the circuit and then separate at the feeding and delivery ends. These aprons are made of open-work and guided about the guide-wheels E of the drying-chamber A and the wheels E' of the conditioning-chamber P. The apron B is also guided about the large wheels D at the feeding end and the wheel G at the delivery end, said wheels D and G being outside of the chambers. The apron C is further guided away from the apron B by wheels F, arranged outside of the chambers. The aprons travel, as indicated by the arrows, and the wheels may be driven in any suitable manner to impart motion to the aprons.

The material is practically dried during its passage through the drying-chamber A, and when it enters the chamber P it is in a state suitable to the conditioning treatment, which

consists in forcing air, gas, or steam as required through the materials and aprons. The nature of this conditioning treatment is well known in the textile art and need not be referred to in this application more than to indicate that such treatment as may be required is performed in the chamber P by circulating medium after the materials have been dried.

10 The means for circulating the drying medium in the chamber A is indicated with the fan and heater of the conditioning side chamber H and need not be further illustrated. The two chambers A and P have each their own side chambers H, so that the circulating medium of one chamber does not pass through the other chamber. The nozzle or injector R of the conditioning side chamber H may be omitted from the side chamber of the drying-chamber A.

15 While I speak of "guide-wheels" for the aprons, I wish it to be understood that I use that term in a generic sense as including any form of a guide about which the aprons are guided so as to pass from one level to another.

20 Where the aprons pass about wheels E E', they are required to lie close together to prevent the textile material shifting.

25 In the horizontal travel of the aprons between the wheels E E' E' the aprons B and C are caused to separate to the requisite distance to remove all excessive pressure from the material being dried. To accomplish this, I provide guides of angle-iron L M, upon which the sprocket-chains K of the aprons B C are caused to run and by which they are supported, as shown in Fig. 3. The guides L M may be made in any suitable manner so long as they support the aprons at different elevations. These aprons are ordinarily formed of two endless sprocket-chains connected by open-work webbing of metal or cross-slats, so as to permit free passage of air. The sprocket-chains travel on the guides in such a manner as to prevent passage of air around the aprons. As a further precaution to prevent the air passing upward through the aprons C and B and adjacent to the guides L transversely-arranged boards Q 30 may be arranged closely to the under sides of the guide L, as indicated in dotted lines, Fig. 3, to act as shields and direct the air away from the chains and guides and from the lateral edges of the aprons which would naturally contain less of the material to be dried. These shield-boards may be or may not be used, as desired. I do not confine myself to any particular construction of apron. The aprons may be driven by the wheels E' and G 35 being formed as sprocket-wheels and meshing with the chains K of the aprons. By having the aprons separated in the horizontal travel it is evident that the material is allowed to spread and expand and assume a

most excellent condition to be acted upon by 65 the downdrafts of air, steam, or gases. While perfectly free during the horizontal travel, the material is held tightly between the aprons when passing about the rollers E or E', or, in other words, when passing from one 70 level to another, whether up or down. This prevents displacement or congestion of the materials between the aprons.

75 It will be understood that while the apron B supports the material during the first and third horizontal passage through the chambers A and P the apron C supports it during the second horizontal passage through the chambers of the machine, so that the two aprons B and C alternately shift their operative portions from above to below the material, and vice versa, and at the same time reverse the material. In case of cotton or loose fiber it is evident that the separation of the aprons would be most beneficial, as it 80 would permit the cotton to open or expand and quickly dried and be delivered from the machine in a fluffy and desirable condition.

85 While I prefer the construction shown, I do not confine myself to the details, as they 90 may be varied without departing from the spirit of the invention.

Having now described my invention, what I claim as new, and desire to secure by Letters Patent, is—

95 1. In a machine for drying and conditioning materials, the combination of a drying-chamber and a conditioning - chamber arranged end to end, guide-wheels for guiding two endless aprons back and forth through each of said chambers, two endless aprons for holding the materials to be treated between them and guided about the guide-wheels, and means within the chambers for separating the two aprons slightly to remove pressure from the materials while passing between the guide-wheels.

100 2. In a machine for drying and conditioning materials, the combination of a drying-chamber and a conditioning - chamber arranged end to end, guide-wheels for guiding two endless aprons back and forth through each of said chambers, two endless aprons for holding the materials to be treated between them and guided about the guide-wheels, and means consisting of horizontal guides L M within the chamber for separating the two aprons slightly to remove pressure from the materials while passing between the guide-wheels.

105 3. In a machine for drying and conditioning materials, the combination of a drying-chamber and a conditioning - chamber arranged end to end, guide-wheels for guiding two endless aprons back and forth through each of said chambers, two endless aprons of open-work with sprocket-chains on their edges for holding the materials to be treated be-

tween them and guided about the guide-wheels, and means consisting of guides within the chambers for supporting the sprocket-chains and thereby separating the two aprons slightly to remove pressure from the materials while passing between the guide-wheels.

4. In a machine for drying and conditioning materials, the combination of a drying-chamber and a conditioning - chamber arranged end to end, guide-wheels for guiding two endless aprons back and forth through each of said chambers, two endless aprons for holding the materials to be treated between them and guided about the guide-wheels, means within the chambers for separating the two aprons slightly to remove pressure from the materials while passing between the guide - wheels, and means for circulating drying and conditioning media separately

through the respective drying and conditioning chambers.

5. In a machine for drying and conditioning textile materials, the drying and conditioning chambers arranged end to end, guide-wheels for said chambers, two endless aprons guided by the guide-wheels so as to pass alternately back and forth in each chamber and through the two chambers successively, and separate means for each chamber for respectively circulating the drying and conditioning mediums.

In testimony of which invention I hereunto set my hand.

JOHN H. LORIMER.
